US0D1070090S

(12) **United States Design Patent** (10) Patent No.: **US D1,070,090 S**
(45) Date of Patent: ** Apr. 8, 2025

(54) **DIALYSIS MACHINE**

- (71) Applicant: **Quanta Dialysis Technologies Ltd.**,
Warwickshire (GB)
- (72) Inventor: **David Alastair Spurling**, Warwickshire
(GB)
- (73) Assignee: **QUANTA DIALYSIS
TECHNOLOGIES LTD.**,
Warwickshire (GB)
- (**) Term: **15 Years**
- (21) Appl. No.: **29/761,125**
- (22) Filed: **Dec. 7, 2020**

The ornamental design for a dialysis machine, as shown and described.

DESCRIPTION

FIG. 1 is a perspective view of a design for a dialysis machine; and,

FIG. 2 is a right side-view of the design for the dialysis machine of FIG. 1.

The broken lines contained in the figures depict portions of the dialysis machine that form no part of the claimed design.
